LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

LIQUID-FUEL BURNER.

Application filed February 26, 1921. Serial No. 448,110.

To all whom it may concern:

Be it known that I, LEE S. CHADWICK, a citizen of the United States, residing at Shaker Heights Village, in the county 5 of Cuyahoga and State of Ohio, have invented a certain new and useful Improvement in Liquid-Fuel Burners, of which the following is a full, clear, and exact description, reference being had to the accompanying drawings.

This invention relates to liquid fuel burners of the class employing wicks and involving wick raising means having a limited movement and it has to do more particularly 15 with means for automatically adjusting the wick with respect to the wick raising means each time the wick is cleaned or trimmed, thereby to compensate for the shortening of the wick. The invention has reference also 20 to a unique wick trimming device.

The fundamental purpose of the invention is to provide in burners of the class above mentioned an adjustable stop for limiting the movement of the wick raising 25 means, especially in a direction to elevate the wick; a lock for holding the stop in a fixed position; and a device, preferably a wick trimmer, which is adapted to be engaged over the wick guide and restrict the 30 wick against being raised above a predetermined point, the device being designed to cooperate with the aforesaid lock to render it temporarily ineffective so that the wick may be adjusted by the wick raising means 35 to compensate for the part consumed or trimmed off.

Further objects are to provide a comparatively simple and inexpensive construction involving the foregoing features that is especially convenient of use, thoroughly efficient, and which lends itself readily to economical manufacturing methods, the majority of its individual elements consisting of sheet metal stampings which interlock and 45 interfit in such manner as to reduce to a minimum the labor of assembling the parts.

The foregoing objects, and others which will become apparent as this description proceeds, are attained in the embodiments 50 illustrated in the drawings accompanying and forming a part thereof and set forth in the claims appended hereto.

In the drawings, Fig. 1 is a side elevation of a burner incorporating my improvements; Fig. 2 is a plan view of the wick

trimmer; Fig. 3 is a fragmentary side elevation of the burner with the trimmer applied thereto in a position to trim the wick and cooperate with the locking mechanism to render it ineffective and release the stop, 60 a part of the trimmer and burner being shown in section; Fig. 4 is a fragmentary plan view of the burner; Fig. 5 is a section on the line 5—5 of Fig. 4; Figs. 6 and 7 are sectional details on the respective lines 65 6—6 and 7—7 of Figs. 4 and 5; and Fig. 8 shows a modification of the invention.

The burner wherein I have shown my improvements incorporated is of the well-known type involving inner and outer wick 70 tubes 1 and 2, respectively, between which a cylindrical wick 3 is guided and is adapted to be raised and lowered by means of the wick raising spindle 5 which is encased within a tube 6 that is supported from the 75 outer wick tube 2 and carries pinions or star wheels 7 at its inner end which cooperate with the wick. A hand wheel 8 is applied to the outer end of the spindle for turning it. The foregoing parts being common to both 80 forms of the invention herein illustrated, are designated by the same reference numerals in all views of the drawings.

In the form of the invention illustrated in Figs. 1 to 7, a bracket 10 is fastened to 85 the tube 6 a suitable distance inward of its forward end, and within a notch 11 thereof is fulcrumed a locking element 12 that is shown as formed of sheet metal—as is also the bracket 11—and as having fingers 15 depending on opposite sides of the tube 6 in a position to engage a thrust plate 16 that loosely surrounds the tube and has an extension 17 confined between the opposed sides of the locking element forwardly of 90 the bracket 10. A sleeve 18 is shown as surrounding the tube 6 immediately adjacent the bracket 10. Mounted for longitudinal and rotary movement upon the forward end of the tube 6 is the hub portion 19 of a stop 100 plate 20, the plate having a rearwardly directed peripheral flange that is serrated to provide teeth 21 wherewith the nose of the locking element 12 is adapted to interengage. A spring 25 is interposed between a 105 collar 26, situated immediately inside the hand wheel 8, and the locking plate 20 to retain the latter in its innermost or normal position against the sleeve 18. The influence of the spring 25 is transmitted to the 110

2
fingers 15 of the locking element 12 through the intervention of the stop plate 20 and thrust plate 16 to rock the locking element upon its fulcrum and retain its nose in engagement with the teeth 21 and its rear end elevated to the position shown in Figs. 1 and 5.

The plate 20 is provided with spaced stops 27 and 28, the latter having two abutment portions 28^a and 28^b, (Figs. 4 and 6). The hand wheel 8 is provided with a projection 30 that engages the stops 27 and 28 to limit the angular movement of the spindle 5, thereby to restrict the wick against being raised or lowered beyond a given point in the respective directions.

The wick trimmer, shown in Figs. 2 and 3, comprises a sheet metal shell 35 designed to fit down over the top of the wick tubes 20 with an inclined annular portion 36 which engages with the upper ends of the tubes and bears upon the top of the wick when the wick is elevated to the plane of the tube ends. The inclined portion 36 has a series 25 of apertures the ends whereof constitute cutting lips 37 for trimming off the charred portion of the wick when the trimmer is rotated by means of a handle 38 that is fixed to its center. Beyond the outer wick tube, 30 the shell of the trimmer extends downwardly and outwardly and terminates in a peripheral flange 39 which engages the rear end of the locking element 12, the parts being so proportioned that when the portion 36 of 35 the trimmer bears upon the wick tubes, the locking element is rocked to ineffective position, as indicated in Fig. 3. When the element is thus rocked, it forces, through its fingers 15 and the thrust plate 16, the stop plate 20 outwardly along the tube 6 against the tension of spring 25 until the stop plate is in contact with or in very close proximity to the inner end of the projection 30 of the hand wheel. This results in a disengagement 40 of the locking element with the teeth of the stop plate so that the stop plate, and consequently the spindle, are at liberty to be rotated in a direction to elevate the wick except as restricted by the limited movement of the wick due to the presence of the trimmer on the wick tubes. It will be seen, 45 therefore, that the wick may be elevated into firm contact with the inclined portion 36 of the trimmer after the trimmer has been rotated or oscillated to trim off the charred portion of the wick. This determines then the extent to which the stop plate may be turned, through the engagement of the projection 30 of the hand wheel with the abutment 28^a of the stop 28. The trimmer may 50 now be removed, allowing the parts to resume normal position with the stop plate and locking element interengaged so as to hold the stop plate against further movement. When the stop plate is in normal

position, the projection 30 of the hand wheel escapes the abutment 28^a of the stop 28 and engages the abutment 28^b thereof. This additional angular movement allowed to the spindle after the parts resume normal position permits the wick to be elevated to "high" position above the wick tubes. 70

Thus it will be seen that my invention provides a thoroughly reliable means for limiting the travel of the wick, and one 75 which is adjusted each time the wick is cleaned to compensate for the portion trimmed off, the adjustment being in effect automatic in that it is accomplished by the mere trimming of the wick and requires no additional attention or care.

It will be observed that practically all of the elements involved in the device are constructed of sheet metal, and that they interfit in such manner as to obviate the need 80 of pins, rivets, bolts or other securing or pivotal means the locking element 12 being designed to fit over the upper end of the bracket 10 so as to have bearing in the notch 11 thereof, and it is held in such position 85 by the spring 25, through the intervention of the lock plate 20 and thrust plate 16, the latter plate being held in proper angular position by its extension 17 being confined between the side walls of the locking element 12. 90

In Fig. 8 the trimmer 40 is made to fit down over the outer wick tube so as to prevent its rocking on the burner, and its outwardly directed portion 41 is designed to 100 pass down to the rear of the inner end of the locking element 42. This element is shown as pivoted upon a pin 43 supported by a bracket 44 that rises from the tube 6. In other respects, the present form of the 105 invention is identical with the one above described. As to operation, in the latter modification the holding of the locking element 42 in ineffective position is accomplished by the presence of the flange of the 110 trimmer between the comparatively straight inner end of the locking element and the opposed portion of the burner, thus obviating the need of holding the trimmer down 115 against the burner tubes while making the wick adjustment.

To remove the wick from the burner, as for the purpose of replacing it by a new wick, the rocking element (12 in the first form of the invention and 42 in the second) 120 may be rocked by the operator to disengage it from the stop plate 20, after which the spindle may be rotated freely to elevate the wick beyond the pinions or star wheels 7 so that the operator may lift it from the 125 burner; the part can be retained in the same condition while inserting a new wick.

Having thus described my invention, what I claim is:—

1. In combination with a burner involv- 130

ing a wick guide and means for raising the wick, a movable stop for limiting the movement of said means, means for locking said stop against movement, and a device adapted to be placed over the wick guide and serving to arrest movement of the wick in an upward direction above a predetermined point, said device when in such position cooperating with and rendering the locking means ineffective.

2. In combination with a burner involving a wick guide and means for raising the wick, a movable stop for limiting the movement of said means, means for locking said stop against movement, and a wick trimming device adapted to be placed over the wick guide and serving to arrest movement of the wick in an upward direction above the top of the wick guide, said device when in such position cooperating with and rendering the locking means ineffective.

3. In combination with a burner involving a wick guide and means for raising the wick, a movable graduated stop having a main and an auxiliary abutment for limiting the movement of the wick raising means, means for locking the stop against movement, and a device adapted to be engaged over the wick guide to restrict the wick against being raised above the top of the guide, said device when in such position cooperating with the locking means for rendering it ineffective and for shifting the stop so that its auxiliary abutment serves to limit the movement of the wick raising means, the stop assuming normal position upon the removal of the aforesaid device thereby to cause the main abutment to serve as a stop for the wick raising means.

4. In combination with a burner involving a wick guide and a wick raising spindle, the spindle having a stop engaging portion, a stop supported in operative relation to said portion and movable angularly with respect to the spindle, means for locking the stop against angular movement, and a device adapted to be placed over the wick guide and serving to limit the movement of the wick in an upward direction above a predetermined point, said device when in such position cooperating with and rendering the locking means ineffective.

5. In combination with a burner involving a wick guide and a wick raising spindle, the spindle having a stop engaging portion, a stop supported in operative relation to said portion and movable axially of and angularly with respect to the spindle, said stop having a main and an auxiliary abutment spaced axially with respect to each other and wherewith the stop engaging portion of the spindle is arranged to engage, means for locking the stop against angular movement, and a device adapted to be placed over the top of the wick guide and serving to re-

strict the wick against being raised above the top of the wick guide, said device when in such position cooperating with the locking means for rendering it ineffective and for shifting the stop axially of the spindle so that its auxiliary abutment serves to limit the movement of the wick raising means, the stop assuming normal position upon the removal of the aforesaid device thereby to cause the main abutment to serve as a stop for the spindle.

6. In combination with a burner involving a wick guide, a wick raising spindle and a tube encasing the spindle and beyond the end whereof the spindle projects; a bracket supported by and spaced inwardly from the end of the tube, a locking element pivotally supported by the bracket and having fingers depending on opposite sides of the tube, a hand wheel secured to the spindle beyond the end of the tube, a collar disposed inside the hand wheel, a stop plate slidable along the tube, a spring interposed between the collar and stop plate and tending to force the stop plate toward the fingers of the locking element thereby to rock the locking element on its pivot and project a part of it into interlocking engagement with parts of the stop plate, stops carried by the stop plates and spaced angularly apart, the hand wheel having a projection for engagement with said stops, and a device adapted to be placed over the top of the wick guide to restrict the wick against being raised above a predetermined point, the device having a part for cooperation with the locking element to rock it on its pivot whereby the locking element will be withdrawn from interlocking engagement with the stop plate and through its fingers will move the stop plate along the tube in opposition to the aforesaid spring.

7. In combination with a burner involving a wick guide, a wick raising spindle, and a tube encasing the spindle and beyond the end of which the spindle projects; a sheet metal bracket supported by the tube and spaced inwardly from the end thereof, said bracket having a notch in its forward side adjacent its upper end, a sheet metal locking element having an aperture through which the end of the bracket is engaged so that the element has pivotal bearing within the notch of the bracket, the element having fingers depending on opposite sides of the tube, a thrust plate loosely mounted upon the tube forwardly of the bracket and having a part interfitting with the locking element to prevent the thrust plate from turning with respect to the tube, a stop plate slidably mounted upon the tube adjacent its end, the stop plate having a series of peripheral teeth wherewith the forward end of the locking element is adapted to engage for holding the stop plate against angular

movement, a hand wheel secured to the outer end of the spindle, a collar situated immediately inside the hand wheel, a spring interposed between the collar and stop plate, 5 stops carried by the stop plate and spaced angularly apart, one of said stops having a main and an auxiliary abutment portion, the hand wheel having a projection for engagement with said stops, and a device 10 adapted to be engaged over the wick guide for restricting the wick against being elevated above the predetermined point, said device having a part for cooperation with the rear end of the locking element to rock 15 the element upon its pivot thereby to disengage it from the peripheral teeth of the lock plate and, through its fingers and the intervention of the thrust plate to move the stop plate outwardly along the tube, the 20 aforesaid projection of the hand wheel, when the parts are in said condition, being arranged to engage the auxiliary abutment of the aforesaid stop.

8. A trimmer for wicks of oil burners of 25 the type involving inner and outer wick tubes, the upper edge of the outer wick tube being higher than the corresponding edge of the inner wick tube, said trimmer consisting of a circular shell adapted to fit 30 down over the outer wick tube and having a frusto-conical portion bearing upon the tops of the tubes, said portion being provided with apertures, the edges whereof are 35 within the plane of the under surface of said portion and constitute cutting lips for engagement with the top of the wick when

the top of the wick is substantially flush with the tops of the wick tubes.

9. A trimmer for wicks of oil burners of 40 the type involving inner and outer wick tubes, said trimmer consisting of a member that is provided with an annular part having a smooth under surface arranged to bear upon the tops of the tubes and wick, said part being provided with apertures the 45 edges whereof constitute cutting lips that are within the plane of said smooth under surface whereby said surface serves to smooth the wick after said cutting lips have trimmed the wick or removed the char therefrom. 50

10. A trimmer for wicks of oil burners of the type involving inner and outer wick tubes, the upper edge of the outer wick tube being higher than the corresponding edge 55 of the inner wick tube, said trimmer consisting of a circular shell adapted to fit down over the outer wick tube and having a frusto-conical portion bearing upon the tops of the tubes, said portion being provided with apertures the circumferentially spaced-apart edges whereof converge inwardly with respect to the radial axes of 60 said apertures and constitute cutting lips, whereby, when the trimmer is rotated alternately in opposite directions, said lips will tend to flare outwardly the fibers of the wick against the outer wick tube. 65

In testimony whereof, I hereunto affix my signature.

LEE S. CHADWICK.
